UNITED STATES PATENT OFFICE.

CHARLES RICHARD GREGORY, OF LONDON, ENGLAND, ASSIGNOR OF ONE-HALF TO
NEIL McBEATH, LONDON, ENGLAND.

TOY BOOMERANG.

Application filed June 20, 1925. Serial No. 38,550.

To all whom it may concern:

Be it known that I, CHARLES RICHARD GREGORY, a subject of the King of England, and resident of London, in the Kingdom of 5 England, have invented new and useful Toy Boomerangs, of which the following is a specification.

This invention relates to a toy of the type in which missiles are discharged by the 10 release of a spring, trigger or the like.

The object of the invention is to provide a new, simple and consequently inexpensive toy comprising a suitable easily manipulated appliance for discharging, more particularly, a boomerang placed upon a support when a spring is released; the energy imparted to the boomerang being sufficient to cause it to return, as such missiles do, to or 20 near to the place from which it was discharged.

With the above mentioned object in view, the invention comprises a suitable support from which a boomerang is discharged by a spring.

25 The invention comprises further, any suitable means for holding the support in the hand whilst arranging the boomerang in position thereon and manipulating the spring to discharge the boomerang.

30 The invention consists, further, in a suitable construction of the toy, involving a combination and arrangement of parts as hereinafter described with reference to the drawings.

35 The invention consists, further, in the provision of and combination with the discharging appliance of boomerangs suitable for the purpose intended.

Reference being had to the accompanying 40 drawings:

Figure 1 is a perspective view of the toy; Fig. 2 is a perspective view showing clearly some of the parts of which the toy is preferably made; Fig. 3 is a front view of a principal part of the toy illustrating the spring and its arrangement thereon; Fig. 4 shows the boomerangs used—two of them drawn to a reduced scale—and illustrating modifications in the their shape; Fig. 5 illustrates the manner of holding the toy; Fig. 6 illustrates the manner of manipulating the toy to discharge a boomerang; Fig. 7 shows means for holding the support, hereinafter referred to, in desired positions.

According to this invention, a preferred 55 construction comprises a piece of flat substance or material, such as sheet tin, cardboard, celluloid or the like 1 having longitudinal disposed inturned integral flanges 2.

This piece of material constitutes the main 60 part or base of the manipulative part of the toy. It carries a spring 3, preferably consisting of a suitably coiled length of wire 65 of which one end portion 4 is suitably secured to the base 1 as, for instance, by clips which may be formed by slitting the part 1, as shown at 6, and bending the intervening part of the substance over the wire in opposite directions as shown respectively at 7, 8. The other end portion of the wire extends slantingly upwards and rests upon the upper end of the adjacent flange 2; the base 1 and flange having been cut away, as shown at 9 so that the extremity of the spring need not extend beyond the upper edge thereof 75 when in the normal position shown. The end of this part of the spring is preferably bent at right angles to constitute a convenient piece 10 for operating the spring.

The base 1 is partly enveloped by a folder 80 which may consist of a piece of paper or other suitable and thin material which is creased or otherwise rendered capable of folding at 11, 12. From this latter crease to its extremity 13 the folder is reduced in 85 width to pass between the inner edges of the flanges 2 contiguous to the spring, being held in that position by a more substantial sheet 14 of suitable material which is slid beneath the flanges 2. The intermediate part 15 is 90 capable of folding into contiguity with and thus forming a facing to the base 1, to which it may be adhesively secured if desired. The remaining part of the folder constitutes a support 5 for the boomerangs and may have 95 imprinted thereon representations in different positions as shown at 16, 17, 18 of Fig. 1 for a purpose hereinafter referred to. Although this support can be held at any desired angle by the hand it may be provided 100 with any suitable means for the purpose as, for instance, a strip of material 19 secured to the underside thereof and capable of sliding movement within a retaining loop 20 secured to the intermediate part of the folder 105 as shown. The toy, as shown in Fig. 1, may be faced on both sides by ornamental paper, which may have instructions imprinted upon

it, or the edges may be bound with suitable binding strips, or, further, the toy may be inserted in a paper envelope which may receive the boomerangs. If desired, a pocket 5 for the boomerangs may be adhesively or otherwise secured to the front or back of the toy, as desired.

The boomerangs may be of any suitable material, such as celluloid and of any suitable shape such as shown for example at Fig. 10 4 wherein one arm of each boomerang is arranged substantially at right angles to the other and is slightly longer. The flight is improved by bending downwardly the end 15 portion of the longer arm as at 22 or the curvature may extend throughout its length as shown at 23.

The toy is held by the hand as shown in Fig. 5 with the support raised. The boomerang is placed in one of the positions indicated on the support. The trigger 10 is then drawn rearwardly by the thumb of the other hand (Fig. 6) and the boomerang adjusted to the required position by the first 25 finger of the same hand. Release of the trigger will then project the boomerang with a force and to a distance depending in ex-

tent upon the position to which it was adjusted upon the support.

If the boomerang be discharged with the support horizontal the flight will be straight; the boomerang on its return journey deviating only slightly to the right from its outward course and slightly below the level at which it was launched so that it can be conveniently caught by the right hand. If, however, the support be slightly raised the flight will be more circular, the boomerang returning in many instances on to the support itself. 35 40

I claim:

A toy comprising a base having a spring thereon, means, such as inturned flanges on the base for retaining a cover for the spring, a folder of which one end portion is held 45 to the base by insertion between it and the aforesaid cover, its intermediate part constituting a facing or backing for the other side of the base, and its free end portion constituting a support for boomerangs in position to be discharged therefrom, said parts constructed and combined substantially as described. 50

CHARLES RICHARD GREGORY.
